ATTACHMENT CORD ANCHORAGE WITH
BALL CONTACT SWITCHShirley P. Morse, East Haven, Conn., assignor to
The A. C. Gilbert Company, New Haven, Conn.,
a corporation of Maryland

Application June 7, 1945, Serial No. 597,998

6 Claims. (Cl. 200—157)

1

This invention relates to hand held bodily maneuvered electrical appliances and particularly to arrangements of electric switching mechanism therein combined with attachment cord anchorage structure of the general type disclosed in my copending application Serial No. 553,826, filed September 13, 1944, now Patent Number 2,432,067, issued December 2, 1947.

In said patent there is proposed an arrangement of working parts of an electric switch so organized in juxtaposition to a rugged protective anchorage for an electric attachment cord entering the appliance that both may combine to form a torpedo-shaped end of an appliance having a tapering streamlined outer contour. The constructions there proposed contemplate in one form a hollow cup-shaped, switch operating, ring handle given rotary bearing on the periphery of the torpedo-shaped casing of the appliance in conjunction with a spring-urged pressor plate in axially outboard relation to such ring handle operative conductively to bridge rolling switch contact balls and to bias such balls into engagement with stationary circuit contacts.

In other forms disclosed in the above said patent it is proposed to provide the ring handle with a central bearing hub and to house such spring-urged pressor plate within the cup-shaped interior of the hollow ring handle of the switch while ringed about such bearing hub so that both the pressor plate and its biasing spring are carried by and revolve bodily with the ring handle and the contact balls of the switch when manually actuated.

The present improvements aim to combine the comparative simplicity and compactness of appliance casing structure that characterizes the last mentioned arrangement with certain desired mechanical and electrical functions of a spring-urged pressor plate which according to the present improvements may or need not turn in unison with the switch handle and the rolling switch contact balls. Movement of such balls over a circular path relative to a non-turning ball-bridging conductive pressor plate enables shallow sockets or holes in the plate to serve as stationing detents for the balls and may further serve to wipe clean the mutually contacting surfaces of balls and plate as well as to contribute mechanically to the abruptness of snap action with which the balls make and break contact with the stationary circuit terminals of the switch.

The present improvements also permit a greater area of current conducting contact between

2

rolling contact balls and a ball-bridging pressor plate that may be contained within the hollow of a cupped shape switch operating ring handle by enabling the balls to be seated in spherically contoured dents, or in holes of smaller diameter than the balls, provided in the pressor plate.

These and other objectives will be made clear in the following description of one embodiment of the present improvements illustrated in the accompanying drawings wherein:

Fig. 1 is a view taken mostly in section on plane 1—1 in Fig. 5 extending lengthwise through the stub end of an encased portable electrical appliance incorporating a control switch and attachment cord anchorage structure embodying the present invention.

Fig. 2 is a view similar to Fig. 1 taken in section on the planes 2—2 in Fig. 5 looking in the direction of the arrows.

Fig. 3 is a crosswise view taken in section through the ring handle of the switch on the plane 3—3 in Fig. 1 looking in the direction of the arrows.

Fig. 4 is a crosswise view taken in section through the switch retaining nut on the plane 4—4 in Fig. 2 looking in the direction of the arrows.

Fig. 5 is a crosswise view taken in section through the stub end of the casing on the plane 5—5 in Fig. 1 looking in the direction of the arrows.

Fig. 6 is an exploded perspective view of certain operating parts of the switch removed from the stub end of the appliance.

Fig. 7 is an illustrative diagram of circuit connections.

Fig. 8 is a perspective view of a non-turnable pressor plate that may be substituted for the turnable pressor plate of Fig. 6 in conjunction with casing stop projections modified to cooperate therewith as key studs.

The housing of the appliance includes a hollow casing 12 of which only a stub end portion is herein shown. In keeping with modern design the entire casing may be elongated and streamlined in outer contour to terminate in a torpedo nose shape as shown in the drawings. Reference is made to my copending application, Serial No. 553,826, filed September 13, 1944, now Patent Number 2,432,067, for a full showing of a casing of this type which lends itself to being molded from any suitable electrical insulative material including the many so-called "plastics." Preferably the casing is of suitable crosswise girth to be grasped in the palm of the hand and encircled

by the operator's fingers for holding and maneuvering the appliance.

That portion of the casing shown in the drawings is longitudinally ribbed internally at 14 to receive the body of an electric motor 15, one end of which is firmly but detachably secured by holding screws 17 to anchorage lugs 16 formed internally on the casing wall. At the opposite end of motor 15 there is a projecting motor shaft (not shown) together with operating connections to the movable parts that perform the working duty of the appliance, such as a blower fan in a portable hair drier, a projecting drill spindle, a hair clipping blade, or any analogous working tool. Motor 15 is fed with current through the wires 49, 50 of an attached cord 22. The aforesaid copending application may be referred to for illustrative construction of a more complete appliance in which the present improvements may be incorporated to advantage.

The stub end of the casing 12 carries an assemblage of electric current switching parts and attachment cord anchorage structure embodying the present improvements. For the particular objectives of this invention, casing 12 terminates at a transverse or crosswise extending detachable web wall 20 which may be of the same kind of insulative material as the casing and secured to the latter by the same holding screws 17 that have threaded engagement with the body of electric motor 15. Web wall 20 is centrally brushed by an axially elongated rigid tubular conduit structure inclusive of member 21 and fixedly lodged therein. This conduit member may be of metal or of insulative material and may be held rigid with wall 20 by bonding it fixedly therein during the molding operation by which wall 20 is formed. If preferred, conduit member 21 may be formed as a molded homogeneous extension of the insulative material of wall 20. In any event, it affords what may be termed a hollow boss projecting outward from the stub end of casing 12 constituting conduit structure one end of which opens outside the casing and the other end of which opens to the interior of the casing.

The attachment cord 22 is armored at its appliance connecting end by a molded sheath 23 of flexible resilient insulative material and this sheath terminates in an outflaring flange 24 that overhangs the inner end of tubular member 21 to prevent withdrawal of the attachment cord outward from conduit member 21.

The upper or inside face of web wall 20 has fixedly secured thereagainst by rivets 27 the binding-posts 28 comprising bent metal clips to which electric circuit wires may be attached by soldering or otherwise. An electric circuit that includes such wires and the motor 15 is diagrammed in full lines in Fig. 7. The opposite headed-over ends of rivets 27 are sunken a little in counterbores 29 at the outer mouths of holes in web wall 20 through which the rivets extend. There are additional and similar counterbores which may be left blank or vacant of rivet heads, as shown at 31. All of the counterbores are spaced circumferentially in a common circular track concentric with the common longitudinal central axis of casing 12 and conduit member 21. The rivet heads that are exposed on the outer side of wall 20 constitute circuit terminals and the rivets 27 serve as conductors leading to the inner side of wall 20 where they are in electrical connection with the attachment cord wires through binding posts 28.

The movable contacts, or circuit making and

breaking elements, of the switch include electrically conductive balls 35 of equal diameter adapted to seat fully on the bottoms of the counterbores 29 and/or 31 so as to reach and make electric contact with any heads of rivets 27 that occupy such counterbores. Contact balls 35 are maintained at constant spacing from one another in their circular path of travel regardless of what positions they all occupy along such path due to each ball being caged in a slightly oversize hole 36 in a ball impelling disc 37 which is removably fixed in the peripheral rim portion of a ring-like switch handle 38 and thus comprises means for transmitting motion from handle 38 to balls 35 in unison. This handle is hollow and molded from insulative material to a shape providing the hub 39 and the ventilating apertures 40. Thus ring handle 38 is cup-shaped.

Hub 39 sleeves over and has its sole rotary bearing on the peripheral surface of a rabbet 41 formed in a stationary retaining nut 42 of insulative material that has screw engagement with the threaded outer end of conduit member 21. Thus switch handle 38 is centered with and separated radially from conduit structure 21 and derives axial retaining thrust from the flanged head 43 of nut 42 at rabbet 41. The parts just described are so dimensioned that when nut 42 is screwed up tightly against a stop shoulder on conduit member 21 there is sufficient axial clearance for ring handle 42 to swivel freely between the stationary nut flange 43 and the stationary web wall 20. Nut 42 thus serves as a head for structure 21 in outboard relation to cross wall 20 permitting free turning of handle 38 relatively thereto.

To render the ball impelling disc 37 removable from the body of switch handle 38 for purposes of assemblage it may be fastened thereto by screws, screw threads or equivalent means not shown.

40 This permits a flat pressor plate 45 of conductive material to be received and loosely housed in the hollow space within switch handle between the ball impelling cage 37 and the handle hub 39. Pressor plate 45 is centrally apertured and has sufficient diametrical clearance around a stationary insulative tubular sleeve 46 fitted on conduit member 21 to afford freedom of pressor plate 45 both to rotate and to slide axially. In the assembled relationship of the parts shown in Figs. 50 1 and 2, pressor plate 45 is thrust constantly against the switch contact balls 35 simultaneously in the direction of the web wall 20 of casing 12 by the action of tensioning means in the form of a short spring coil 47 that loosely surrounds sleeve 46 and is circumferentially interposed between conduit member 21 and switch handle 38 in a manner to extend axially from plate 45 to head nut 42, and thereby derive thrust directly from the latter independently of the switch handle. 60 Thus spring 47 is constantly compressed axially between pressor plate 45 and the thrust nut 42. Spring 47 is not imprisoned within the hollow of switch handle 38 and can be removed independently of the latter from the switch assembly. 65 Nevertheless handle 38 does encircle spring 47 and this feature effects considerable saving of axial space.

From the foregoing description of the construction it will be seen that three of the contact balls 70 35 may, in an "off" position of the rotary switch handle 38, occupy three of the vacant counterbores 31 in the insulative web wall 20. The motor 15 is then deprived of current and idle as indicated by broken lines in circuit diagram of Fig. 7. Upon turning switch handle 38 a suit-

able distance to "on" position to swing the contact balls into their full line positions shown in Fig. 7, current from the attachment cord supply wire 49 will pass through one of the binding posts 28, its holding rivet 27, a contact ball 35, pressor plate 45, another contact ball 35, another rivet 27, another binding post 28, lead wire 50, and thus through motor 15 which is constantly in circuit with the return wire 51 of the attachment cord. Now motor 15 will be energized and operate to drive the working tool of the appliance until such time as the switch handle 38 is turned back to its "off" or starting position. The turning of switch handle 38 in either direction beyond the aforesaid "off" and "on" positions may or need not be restricted by any suitable forms of stops such as the projections 52 fixed on web wall 20 to engage opposite ends of the arcuately elongated notches 53 in ball impelling cage 37 of the switch handle.

As the contact balls 35 are swung in unison they become seated or unseated simultaneously with respect to their respective counterbores. In being forced to roll in a common circular path by the loosely engaging impelling cage 37 each ball, because of the seating pressure of spring 47 acting through pressor plate 45 and because of the sharp rim edge of each counterbore 29 or 31, offers resistance to leaving its seat in the counterbore up to the point where increasing muscular torque manually exerted upon the switch handle builds up a tension in the operator's hand which finally overcomes this resistance to unseating of the switch balls. Thereupon there results an abrupt popping up of all three balls simultaneously out of their respective counterbores 29 or 31 producing a quick or snap-action circuit-breaking movement of the current controlling switch parts to inhibit electric arcing and pitting of the contacts. The switch balls 35 may be made of bronze, brass or other metal of good electrical conductivity. When the switch balls reach positions for simultaneously dropping into their respective counterbores over the sharp edges of the latter, the aforementioned lateral looseness of fit of each ball in its hole 36 in handle disc 37 permits the axial urge of pressor plate 45 to snap each ball smartly into its terminal engaging or rivet contacting, fully seated position in its counterbore so that quick making as well as quick breaking of the circuit results.

It will be obvious in Figs. 1 and 2 that no sidewise tugging on attachment cord 40 can act in any way to impair or interfere with free action of the circuit making and breaking parts of the switch because the cord is at all times positively constrained by conduit member 21.

Fig. 8 shows a desirable modification of the stop projections 52 and pressor plate 45 wherein the former are elongated to form key studs 52' extending into the hollow interior of switch handle 38 and occupying stop notches 53 in the pressor plate 45' thus to retentively engage the latter in a manner to prevent its rotary movement while freely permitting its axial movement. This modified and non-turning form of pressor plate contains ball orienting seats 54 spaced on the circle to align axially with the respective counterbores 29 and 31 so that each ball is in each position thereof engaged not only with one of the counterbores but also with one of the seats 54. These seats may comprise merely dents of spherical contour conforming to the surface of the ball or may be holes of smaller diameter than the overall size of the ball. By this expedient the

balls are more certain of making and breaking contact with their respective circuit terminals or rivet heads 27 simultaneously, are enabled to wipe and keep clean the surfaces of pressor plate 45 with which they contact, and are given a greater area of current conductive engagement with the pressor plate for lowering electrical resistance.

Among obvious modifications of other parts herein disclosed, it is noted the pressor plate may be prevented from tuning by giving its central aperture a flat sided or squared sliding fit with respect to the sleeve 46 made of corresponding cross-sectional shape and fast to bushing 21. The web wall 20 may be molded as an integral extension of casing 12. The conduit bushing 21 may have an integral head of the same shape as retaining nut 42 and may have threaded engagement with a thickened variation of web wall 20 to make it removable from the casing.

In view of these and numerous other modifications, the following claims are directed to and intended to cover as broad a scope of substitutes and equivalents as fall within the most inclusive means of the claim language.

I claim:

1. In a hand-manuevered appliance to be supplied with current through an attachment cord, the combination of, a hollow appliance casing, a tubular conduit structure opening into said casing in a manner to admit and constrain an attachment cord entering the appliance, a wall extending crosswise said casing fixedly joining said conduit structure and said casing in substantially rigid relation, spaced current conductive contact balls shiftable simultaneously between circuit controlling spaced positions, a retaining head fixed on the outer end of said conduit structure, a hollow cup-shaped switch handle between said wall and said retaining head including means to impel said contact balls between their said positions, a current conductive pressor plate loosely contained in the hollow of said switch handle bearing against said balls, and a spring thrusting axially against said retaining head arranged to bias said pressor plate toward said balls.

2. In a hand-manuevered appliance to be supplied with current through an attachment cord, the combination defined in claim 1, together with rotation preventing means stationary with the said crosswise extending wall projecting into the said hollow of the said switch handle and retentively engaging the said pressure plate in a manner to prevent rotary movement and permit axial movement of the latter.

3. In a hand-manuevered appliance to be supplied with current through an attachment cord, the combination defined in claim 1, in which the said pressor plate carries ball orienting seats receptive to the said contact balls, together with rotation preventing means stationary with the said crosswise extending wall projecting into the said hollow of the said switch handle and retentively engaging said pressor plate in a manner to prevent rotary movement of the latter.

4. In a hand-manuevered appliance to be supplied with current through an attachment cord, the combination of, a hollow appliance casing, a tubular conduit structure opening into said casing constructed and arranged to admit and constrain against sidewise tugging an attachment cord entering the appliance, a wall extending crosswise said casing fixedly joining said conduit structure and casing in rigid relation, at least one circuit controlling electric switch element

7
shiftable between spaced positions, a retaining head fixed on said conduit structure in outboard relation to said wall carrying a circumferential rotary bearing surface, a switch handle free to be turned relatively to said wall rotatably centered by swiveling engagement with said bearing surface, and motion transmitting means movable by said handle impellingly related to said switch element for shifting the latter between its said positions, together with a spring coil of smaller girth than said bearing surface arranged to exert electric contact-making pressure on said switch element and circumferentially interposed between said conduit structure and said switch handle in a manner to extend axially from said switch element to said head thereby to derive thrust directly from the latter independently of said switch handle.

5. In a hand-maneuvered appliance to be supplied with current through an attachment cord, the combination of, a hollow appliance casing, a tubular conduit structure opening into said casing constructed and arranged to admit and constrain against sidewise tugging an attachment cord entering the appliance, a wall extending crosswise said casing fixedly joining said conduit structure and casing in rigid relation, a plurality of circuit controlling electric switch elements shiftable in unison between spaced positions, a retaining head fixed on said conduit structure in outboard relation to said wall carrying a circumferential rotary bearing surface, a switch handle free to be turned relatively to said wall rotatably centered by swiveling engagement with said bearing surface, motion transmitting means movable by said handle impellingly related to said switch element for shifting the latter between its said positions, and tensioning means for exerting electric contact-making pressure simultaneously on said switch elements including a presser plate encircled by said switch handle and a spring coil thrusting axially against said retaining head arranged to bias said presser plate toward said switch elements, said spring coil being of smaller girth than said bearing surface and circumferentially interposed between said con-

duit structure and said switch handle in a manner to extend axially from said plate to said head thereby to derive thrust directly from the latter independently of said switch handle.

5 6. In a hand maneuvered appliance incorporating an electric circuit adapted to be supplied with current through the wires of an attachment cord, the combination of, a hollow appliance casing, a conduit structure having one of its ends opening outside of said casing and its other end opening into said casing for admitting an attachment cord therethrough to the interior of the casing, a wall extending crosswise said casing fixedly joining said conduit structure and said casing in substantially rigid relationship, at least one conductor presenting an exposed circuit terminal on the outer side of said wall and leading to the inner side of said wall and thereat connected with a wire of the attachment cord, at least one circuit controlling electric switch element shiftable at said outer side of said wall into and out of engagement with said circuit terminal, a retaining head fixed on the outer end of said conduit structure presenting a rotary bearing surface, a switch handle separated radially from said conduit structure rotatably sleeved on said bearing surface for turning movement relative to said casing and axially constrained by said retaining head, and motion transmitting means movable by said handle impellingly related to said switch element for shifting the latter into and out of engagement with said circuit terminal.
